US0D1040363S

(12) **United States Design Patent** (10) Patent No.: **US D1,040,363 S**
(45) Date of Patent: ** Aug. 27, 2024

(54) **SKIN TREATMENT INSTRUMENT**

(71) Applicant: **Hangzhou Jinmo Technology Co., Ltd.**, Hangzhou (CN)

(72) Inventor: **Yun Ling**, Zhejiang (CN)

(73) Assignee: **HANGZHOU JINMO TECNOLOGY CO., LTD.**, Hangzhou (CN)

(**) Term: **15 Years**

(21) Appl. No.: **35/517,259**

(22) Filed: **May 6, 2023**

(80) **Hague Agreement Data**

Int. Filing Date: **May 6, 2023**

Int. Reg. No.: **DM/228899**

Int. Reg. Date: **May 6, 2023**

Int. Reg. Pub. Date: **May 19, 2023**

(30) **Foreign Application Priority Data**

Nov. 22, 2022 (CN) 202230781693.8
